UNITED STATES PATENT OFFICE

152,605

DESIGN FOR AN INSTRUMENT PANEL

Wendell S. Fletcher, South Pasadena, Calif.

Application January 25, 1946, Serial No. 125,967

Term of patent 14 years

(Cl. D52—1)

To all whom it may concern:

Be it known that I, Wendell S. Fletcher, a citizen of the United States, residing at South Pasadena, in the county of Los Angeles and State of California, have invented a new, original, and ornamental Design for an Instrument Panel, of which the following is a specification, reference being had to the accompanying drawing, forming part thereof.

In the drawing:

Figure 1 is a front view of an instrument panel showing my new design; and

Figure 2 is a side view of the same.

I claim:

The ornamental design for an instrument panel, as shown.

WENDELL S. FLETCHER.
